CLAIM

I claim, the ornamental design for a wood stove with heated drying basket and heated cloth rack, as shown and described.

DESCRIPTION

FIG. 1 is a Front Perspective view of a wood stove with heated drying basket and heated cloth rack showing my new design

FIG. 2 is a Back Perspective view thereof;

FIG. 3 is a Right-side Perspective view thereof;

FIG. 4 is a Front view thereof;

FIG. 5 is a Back view thereof;

FIG. 6 is a Right-side view thereof;

FIG. 7 is a Left-side view thereof;

FIG. 8 is a Top view thereof; and,

FIG. 9 is a Bottom view thereof.

In the drawings, the broken lines depict unclaimed subject matter only and form no part of the claimed design.
